COUCH BED

Townsend Foster, New Hartford, N. Y., assignor to
 Foster Brothers Manufacturing Company,
 Utica, N. Y., a corporation of New York

Application February 1, 1938, Serial No. 188,124

7. Claims. (CL. 5-38)

My present invention relates to a couch bed, meaning thereby an article of furniture having two bed sections one of which can be adjusted relative to the other so that in one arrangement there is formed a couch with a back and in the other there is formed either a double bed or if desired twin beds.

The purpose of my present invention is to provide a couch bed of the character described which is of new and improved construction and operation and which is simple and economical in construction, efficient and easy in operation and which is composed of a minimum of moving parts or co-operating parts and which is so constructed that it is not liable to get out of order.

A further purpose is to provide a couch bed of the character indicated wherein the co-operating parts of the two bed sections for holding the movable section in back-forming position or for spacing the movable bed section in double bed position relative to the fixed bed section, consists of parts which are fixed upon the respective bed sections and so are simple in construction and operation and further to form a couch bed wherein the movable section has one edge of its frame adapted to be inserted in a pocket or socket at the back of the fixed bed section so as to hold the movable bed section in position to be the back for the fixed bed section when the article of furniture is to be a couch, and further to have the said co-operating parts adapted to be moved part way towards disengagement with a simple raising of the back and swinging of the back downwardly until the said back or movable bed section is in horizontal position but properly spaced from the fixed bed section so as to form a double bed; a further purpose is to have the said co-operating parts of such character that after the movable bed section has been moved to extended double bed position the movable bed section can be readily and easily entirely disconnected from the fixed bed section by simply raising the side of the movable bed section relative to the adjoining edge of the fixed bed section and then moving the said movable section away as far as needed to be a twin bed.

A further purpose of the invention is to provide new and improved construction of the parts mentioned and to provide combinations thereof which are new and useful and well-adapted to perform the functions required of such a structure.

Further purposes and advantages will appear from the specification and claims herein.

Fig. 1 is a transverse vertical sectional view through one form of a couch bed embodying this

invention, the movable bed section being shown in full lines in its back-forming position and being shown in dotted lines in the position it occupies when moved about half way back to horizontal or bed-forming position. In this view the inner-spring seat cushion is shown in the position it normally occupies when the article is a couch.

Fig. 2 is a similar sectional view of the two bed sections and the seat cushion shown in Fig. 1, but with the movable bed section lowered to horizontal position but still connected to the fixed bed section and with its folding legs dropped to supporting position, the separate movable seat cushion being now moved from its former position to be adjacent the spring unit of the movable section.

Fig. 3 is a sectional view similar to Fig. 2 but with the movable bed section entirely disconnected from the fixed bed section but close thereto as commonly used to form twin beds.

Fig. 4 is a detail perspective view on a larger scale of the right hand rear corner of the couch bed when seen from the back with the movable bed section in raised or back-forming position.

Fig. 5 is a similar perspective view of said parts when the movable section has been initially raised and then swung part way towards horizontal position.

Fig. 6 is an end elevation but with parts in vertical transverse section similar to Fig. 2 of a modified form of couch bed embodying this invention. Fig. 7 is a detailed enlargement of the part of the couch bed shown in Fig. 6 where the two bed sections come together and with the movable bed section in raised position to form the back of the couch.

Referring to the drawings in a more particular description and first to the form of couch bed as shown in Figs. 1 to 5, it will be seen that the couch bed here illustrated comprises a relatively fixed bed section 10, a relatively movable bed section 11 and preferably a separate seat cushion 12 usually of the inner spring construction.

The fixed bed section 10 consists of a suitable spring unit 13 preferably formed of the desired number of coiled springs 14 assembled in proper form upon a suitable lower metal frame 15 with said body of springs commonly having a top border wire 16. The opposite ends of the spring unit 13 and its usual metal supporting frame 15 are suitably supported in raised position by being attached to any proper form of couch ends 17. One such couch end is at each end of the couch bed and essentially consists of a front leg 18 and a back leg 19 and ordinarily having a top arm 55

20 and one or more intervening cross-members 21 towards the top and usually a bottom cross-member 22 near the bottom of the legs. The details of the formation of the spring unit and of 5 the mounting of the spring unit upon the couch ends may be of any conventional form not essential to this invention and so need no further detailed description thereof, except to say that the back or right hand side (as shown in the 10 drawings) of the metal frame for the spring unit of this fixed bed section will have two upstanding metal corner pieces 23 extending above the rectangular metal frame of the spring unit and preferably to about the level of the top of the 15 spring unit 13. Upon the upper part of the back web of each angle iron back frame member 23 there is provided and rigidly secured a rearwardly projecting bracket 24. This is conveniently formed of a short length of angle iron of 20 proper size so that one web thereof 25 may be secured rigidly as by rivets to the back web of the member 23 while the other web 26 of this bracket extends directly rearwardly from the fixed bed section and this web 26 preferably is 25 substantially in line with the forwardly projecting web of the corner member 23 so that the space between the inner faces 27 of the two brackets 26 will be nearly or substantially as great as the length of the spring unit 13 of the fixed bed section. 30

Each bracket 24 is provided on its rearwardly extending web 26 with two strong rigid pins extending from the said web of the bracket towards the other end of the couch bed. The lower pin 28 35 is on the lower part of the bracket 26 and is placed about midway of the width of said bracket and is the short pin. The other or upper pin 29 is longer than the pin 28 and is located upon the upper part of the said web 26 of the bracket and is appreciably nearer the back edge of the bracket or on a line farther from the other web 25 of the 40 bracket than is the short pin 28.

The movable bed section 11 comprises a four-sided preferably rectangular metal frame conveniently formed of angle iron and with front and back side members 30 and 31 respectively and two end cross pieces 32. Upon this frame is placed and securely attached any desired form of spring unit 33 preferably composed in the form 45 of my couch bed shown in Figs. 1 to 5 of a plurality of coiled springs 34 and a border wire 35 extending about the spring unit at its surface away from said frame or at what is the top of said spring unit when this movable section is in bed-forming or horizontal position as shown in Figs. 2 and 3. 50

Spaced slightly back from each end of the movable bed section there is provided a pair of supporting legs 36, the upper ends of which are pivotally attached to the frame as by being so pivotally attached to the downwardly extending web 55 of the front and back side members 30 and 31. Preferably the legs of each pair are connected by a cross bar 37. Each pair of legs is adapted to be folded up closely beneath the frame so as to be practically out of sight when the movable section is placed to be the back of the couch as shown in Fig. 1. When this movable section is to be let down the two pairs of legs will be separately swung down to supporting position as shown in Figs. 2 and 3. Conveniently the legs will be swung 60 downwardly a little past vertical position and then will engage a suitable stop of well-known construction so that there will be no practical possibility of the legs folding accidentally up after they have once been lowered and so moving past

center and the weight of the section placed thereon. It will be understood further that the pivotal connection between the pairs of legs and the frame will be tight enough to hold the legs in 5 frame position when they have been moved to that position.

The two brackets 24 upon the fixed bed section and rigidly located at the opposite ends of the back side of the said fixed bed section form an open-topped socket or pocket adapted to receive 10 suitable rigidly mounted projections upon the movable bed section. In both forms of my invention the projection or projecting portion to fit said open-topped socket or pocket consists of the forward portion of the frame of the movable section and particularly consists of the front side member 30 and the adjacent portions of the two end cross members 32. The detailed construction and the co-operation of these parts is most clearly shown upon the enlarged scale Figures 4 and 5, 15 but the relation of the parts shown in Figures 4 and 5 to the whole bed sections is plainly shown in Figs. 1 to 3 which show transverse sections through both complete bed sections. The forward end of the vertical web 38 of the end members 32 20 of the movable bed section is cut away on its lower portion and preferably on a slanting line, producing a slanting lower edge 39 extending from the front end of said web for the proper distance and producing a shoulder 40 extending out to the free 25 edge of this web 38 as will be most plainly seen in Figs. 4 and 5.

Preferably as indicated in Figs. 4 and 5 the end of the angle iron front side piece 30 of the movable bed section is attached to the opposite angle iron ends 32 within the angle of the latter member. The web 41 of the front angle iron piece of the movable bed section, which web extends rearwardly when this movable section is in upright position as seen in Fig. 4 is cut away at each end 30 from the free edge of the said web inwardly towards the other web 42 forming an end face 43. This end face is spaced inwardly far enough from the original end of the angle iron part 30 to allow the said end faces 43 to safely pass down within 45 the oppositely placed ends of the short pins 28 when the movable bed section is raised to nearly upright position and its forward end dropped into the open-topped sockets or pockets formed by the two brackets 24. In any event the end of the web 50 41 will be so proportioned in the whole structure that the ends 43 will be spaced far enough from the rearwardly facing webs 26 of the two brackets to allow the ends 43 of the web 41 to pass downwardly without striking the short lower pins 28. 55 In the constructions shown in detail in Figs. 4 and 5 the front angle iron side piece 30 is shown as extending well in to the angle of the end pieces 32 and therefore the notch by which the end faces 43 are formed has to be only slightly greater than 60 the total length of the short pin less the extent of the space between the end of the angle iron 30 and the thickness of the web 38 of the end members. When the movable bed section is in any intermediate position such as shown in dotted 65 lines in Fig. 1 the slanting lower edge 39 of the end member 32 at each end will be conveniently riding or sliding along the upper and forward side of the long upper pins 29. This enables the fixed bed section to take a considerable part of the 70 weight of the movable bed section when a person is moving the movable section towards couch-back position or away from that position. During such sliding position especially when the movable bed section is being moved to position to 75

form the back of the couch the extreme front end of the end member 32 at its now lower end will also slide more or less along the rearward face of the web 25 of the bracket 24. At the end of this movement the downward movement of the movable bed section will be arrested and said movable unit permanently held from further downward movement by the shoulders 40 at the end of said slanting face 39 engaging the upper side of the long pins 29 near the brackets 24. Just before coming to this position the notched portion of the front side members 30 which result in the two inwardly cut faces 43 will move past the ends of the short pins 28 so that the lower portion of the slanting edge now rearwardly facing will be forward of the short lower pins 28. It will thus be seen that there are two points of contact upon the now rearwardly-facing slanting edge 39 upon the movable bed section to engage two co-operating forwardly facing points of contact, namely the lower pin 28 and the upper pin 29, at each end of the couch bed. In order to make a three-point contact and especially to hold the movable bed section in back-forming position with the proper slight backward inclination of the back of the couch as said back extends upwardly, there is provided upon the now forward side of the other web 44 of the end pieces 32 a short forwardly extending lug or boss 45 which projects forward from the now forward face of the web 44 against the rearward face of the web 25 of the socket-forming brackets 24. It will be noticed at this time that the arrangement and co-operation of the parts is such that the engaging parts of the movable bed section which enter or co-operate with the oppositely placed brackets 24 do not form a tight wedging action between the three points of contact needed but that the projecting portions of the movable bed section are so designed relative to the size and position of the parts of the brackets 24 that the shoulders 40 will engage the upper side of the upper long pins 29 before a tight wedging action is obtained between the slanting edge 39 and the two pins to the rear thereof and relative to the forwardly projecting boss 45 and the opposite face of the web 25 of the brackets. The purpose of this stopping of the downward movement of the movable bed section before it comes to tight wedging action is to prevent the weight of the movable bed section from driving it so tightly into the apparently wedge-shaped pocket that it could not be removed freely by simply enough power to raise the weight of the movable bed section from said pocket. From the position of parts shown in Figs. 1 and 4 the movable bed section may be shifted to bed-forming position as shown in Fig. 2 by simply raising the bed-section upwardly so that the slanting edge 39 becomes disengaged from the lower pin 28 and then rides more or less closely along the long upper pins 29, the upper or rearward side of the movable bed section being swung downwardly during this upward movement and even when the further or rear side of the movable bed section is being swung downwardly to horizontal position the complete disengagement of the two bed sections will be conveniently prevented by the outer end of the long upper pins 29 engaging the now downwardly projecting web 44 of the front side member 30 of the movable bed section, as most clearly appears in the dotted line position of this frame as shown in Fig. 1 and by the view thereof in Fig. 2. In practice it will be understood that the folding legs will be unfolded while the movable bed section is still in back-forming

position. It will be obvious from the description of the operation of the legs that this unfolding and dropping of the legs can be readily performed when a person has easy access to the rear side of the movable section and that the legs will stay in projecting or down-hanging position as the movable section is being lowered.

In the first form of my invention and as shown in Figs. 1 to 5 the inner spring seat cushion 12 is purposely made slightly narrower than the spring unit 13 and the movable bed section is so proportioned to the parts of the fixed bed section and said inner spring cushion 12 that the spring unit 13 will project appreciably forward from the up-raised frame of the movable unit 11 so as to meet the rear edge of the narrower cushion 12 and project more or less over the spring unit 13 which is permanently secured to the fixed bed section. The purpose of this arrangement is to enable the back of the couch to be spaced only the proper distance back from the front edge of the spring unit 13 and the seat cushion 12. In this way the back of the couch is properly located relative to the front of the couch so that the ordinary person sitting upon the couch may have his back comfortably supported by the back of the couch. It will be seen that the spring unit supporting the frame of the movable bed section is appreciably wider than the spring unit of said section and this excess width of the frame as appears best in Figs. 2 and 3 provides the necessary length of projection upon the said movable section to project down into the open-topped brackets formed by the two brackets 24. This excess width of the frame of the movable section is covered up by sliding the seat cushion 12 from its couch seat position shown in Fig. 1 to its bed-forming position adjacent the spring unit 13 of the movable section when that movable section is lowered to bed-forming position and is to be used to form a double-width bed as shown in Fig. 2.

As an incident to having the upholstered back of the couch close enough to the front of the couch to be a comfortable support for the back of the user the spring unit 13 has its top face when in horizontal position appreciably above the upper surface of the permanently located spring unit 13 of the fixed section. This inequality in the top faces of these two parts is counter-balanced by the thickness of the separate or movable seat cushion 12 as plainly seen in Fig. 2.

If it is desired to make this article of furniture function as twin beds all that is necessary to do after the movable section has been lowered to horizontal bed-forming position as shown in Fig. 2 is to temporarily raise the forward corners of the movable bed sections until the now down-hanging web 41 of the front side member 30 of the frame of said movable section clears the long upper pins 29 of the brackets. If one person has to make this disconnection he can readily raise one corner up until that corner is disconnected from the pin 29 and then shove that end of the movable section a short distance rearwardly so that when he drops that corner it will be clear of the bracket and especially of the pin 29; then going to the other end of the couch bed the same operation is repeated. Obviously then the movable bed section can be moved to any convenient place as it is a complete bed section with its own spring unit in proper position as shown in Fig. 3. To reassemble the section from twin bed position the two sections are brought as closely as possible together and then either separately or together

the two forward corners of the movable bed section are raised over the top pins 29, bringing the parts to the position shown in Fig. 2. Then at this point care will be taken to see that the 5 separate seat cushion 12 is in seat position as shown in Figs. 1 and 3. Then the rear side of the movable section will be raised and the slanting edge 39 of the end members 32 will slide along the upper pins 29 with the forward and 10 now downward edge of the end members beginning to slide along the rear face of the web 25 of the brackets 24. Further swinging of the rear side of the movable section will bring the parts to the relative position shown in Fig. 4 15 and Fig. 1.

In the modified form of couch bed shown in vertical transverse sectional views in Figs. 6 and 7, the fixed bed section 46 comprises a suitable rigid rectangular metal frame 47 supported by couch ends 48 and carrying a spring unit 49. At the back corners of the fixed bed section there are provided the socket-forming brackets 50 conveniently formed of angle iron as already described with regard to similar brackets in the 20 first described construction. Upon each bracket's rearward web 51 there is provided a pin 52 similarly constructed and shaped as is the upper long pin 29 of the first described construction. On the other or forward web 53 of the bracket 25 30 and facing rearwardly therefrom and well down towards the lower portion of the bracket and so well below the pin 52 just referred to, there is a rearwardly facing boss 56. Closely above the brackets 50 there extends along the rear side of the frame 47 and about at the lower part of the spring unit 49 a tacking strip 54 conveniently used for tacking thereto the covering 55 which extends over the spring unit 49. This tacking strip projects slightly to the rear of the spring 35 unit and its rear side covered as it is with the covering 55 forms one point of contact in each socket at the said two rear corners of the fixed bed section. The rear point of contact is the relatively long pin 52 upon the rearwardly extending web 51 of the bracket 50. The third point of contact is the rearward face of the boss 56 upon the front or flat web 53 of the bracket.

Into each socket so formed with its two rearwardly facing points of contact and its one forwardly facing point of contact, namely the pin 52, there is placed the forward edge of the movable bed section 57 when said section is raised to practically upright position to form the back 40 of the couch as suggested in Fig. 7. The movable bed section consists of a rectangular frame forward of ends 58 conveniently angle-iron pieces and a front side 59 and a rear side 60, said sides also conveniently being formed of angle 45 iron. On this rectangular frame is mounted a spring unit 61 which in this case is made as light and thin as practicable as by using link fabric with its opposite sides and edges resiliently connected to the opposite sides and opposite ends of the frame of said movable section as by helical springs in a manner well known in the art and not needing to be described here in detail.

By using this thin spring unit as of link fabric the movable bed section is rendered very much lighter than is the case with the movable section illustrated in Figs. 1 to 5 of this application, where the relatively thick and much heavier bed unit was used. The advantage of this

thinner and lighter unit is that it enables the movable section to be more readily raised out of the open-topped sockets provided at the rear corners of the fixed bed section. The lightness of the movable bed section also renders it easier 5 to swing it rearwardly as it is going down and to raise it from horizontal position, such as that shown in Fig. 6 up to and finally down into back-forming bed position as shown in Fig. 7. With the form of couch bed shown in Figs. 6 10 and 7 and with its consequent thinner bed section upon the metal frame of the movable section, the spring unit 49 of the fixed bed section can be carried all of the way back to the rear edge of the fixed bed section since there no 15 longer has to be a clearance at this rear side into which a thick spring unit upon the movable bed section has to project. In this form of the invention the spring unit 49 upon the fixed bed section is located relatively high as 20 the upper surface of said spring unit is to form the bed surface for this so-called fixed bed section. By comparing Figs. 6 and 7 relative to the other construction it will be seen that the present construction has its metallic frame 47 25 for supporting said spring unit at a much higher level than is the case in Figs. 1 to 5; in fact the frame 47 of the fixed unit is about on a level with the frame of the movable bed section which carries only the thin spring unit 61 30 of link fabric. With this couch bed the extra seat cushion or mattress 62 is for convenience of illustration shown as being flat upon the top of the spring unit 49. This is its position only temporarily since when this article of furniture is being used as a couch this extra cushion or mattress 62 will be set in nearly vertical or upright position at the rear of the couch and leaning against and supported by the then up-raised movable bed section. This position of 40 this cushion is indicated in dotted lines in Fig. 6. When the movable bed section has been let down to form a bed as shown in Fig. 6 the seat cushion 62 will be slid rearwardly to rest flat upon the top of the movable bed section and its upper 45 surface will then be on a level with the upper surface of the spring unit 49 of the fixed bed section. It will be seen furthermore that in this form of the invention the spring unit 49 of the fixed bed section can be of the full width 50 of the said fixed bed section and the seat cushion 62 is of the full width of the movable bed section so that when this article of furniture is put into position for a bed its two thick spring units, namely the unit 49 on the fixed bed section and the seat cushion 62 on the movable bed section cover the full width of the two frames 55 of the structures.

The variation in the mechanical form of the two sockets in this form of bed couch really consists in utilizing the presence of the tacking strip 54 which is above the bracket 50 to provide one of the said contacts in each socket. This contact faces rearwardly as does the rear 60 face of the boss 56 while the pins 52 close to the top of the rearwardly extending web 59 of the bracket 50 provide the forwardly-facing contact upon the fixed bed section.

The end angle iron pieces 58 are cut away at 70 their forward ends as already described in detail with the other form of the invention, forming in this construction the slanting forward portions 63 on the vertical web of the end pieces and providing (as seen in Fig. 7) a rearwardly-facing 75.

edge 64 and a shoulder 65 back or up from the front extremity of the said end pieces 58.

When the movable bed section is to be moved from its extended bed-forming position shown in Fig. 6 its rear or outer side will be raised with the edge 64 of the slanting portion 63 first swinging upon the pin 52 and later as the section gets nearer to upright position the now rearwardly facing edge 64 of said slanting portion 63 will slide down at each end upon the respective pins 52 upon the brackets 50. At the desired end of travel downwardly of this movable bed section the shoulder 65 at the now upper end of the edge 64 will come into engagement with the upper side of the pin 52 and stop further downward movement and permanently and securely hold the movable bed section in upright position to form the back of the couch. It will be understood that the parts are so proportioned that the pin 52 will thus arrest the downward travel of the movable bed section before the movable bed section has come into real wedging engagement with its three points of contact. The now lower end of each front corner 25 of the movable bed section will engage the forward face of the boss 56 upon the fixed bed section and the forward side of the pin 52 will still be engaging the upper portion of the rearwardly-facing edge 64 of the end pieces 58 and 30 the contact between the zone 66 on the movable bed section opposite the tacking strip 54 will be close enough to said tacking strip to prevent any noticeable loose motion between the parts.

35 It will be understood of course that before the movable bed section is thus raised to form the back the seat cushion 62 will have been moved over from bed-forming position upon the movable bed section to temporarily be rested, if 40 most convenient, upon the fixed bed section as shown in Fig. 6. Then when the movable section has been raised to the upright position as shown in Fig. 7 the said seat cushion will be raised to substantially upright position but slanting rearwardly just enough against the upraised movable section to hold the seat cushion, which is now the body-engaging portion of the back of the couch, in position to support the body comfortably.

45 Assuming that the article of furniture is to be moved from couch-forming position as shown in Fig. 7, to bed-forming position as shown in Fig. 6, the seat cushion will be conveniently swung forward to lie flat on the top of the fixed bed section. Then the movable bed section will be raised two or three inches more or less until the front side 59 of the movable bed section engages the pins 52 at either end of the couch. On account of the lightness of this form 50 of movable bed section this movement, it will be seen, can be easily accomplished by any woman. Then the upper edge of the movable section will be swung rearwardly with the front side of this section engaging the pins 52 and swinging thereabouts until the movable section comes substantially to horizontal position. Before the movable bed section will be thus let down it will be understood that the two pairs 55 of legs 61 which will be pivotally or extendibly mounted upon the metal framework of this section will be let down and set in supporting position so that as soon as the section has arrived at horizontal position the legs 61 will support the same in bed-forming position. When the

parts come to this position they will be normally retained in double-bed position as shown in Fig. 6 by the engagement of the front side 59 of the movable section with the pins 52 upon the fixed section. If it is desired however to shift 5 the sections to form therewith twin beds separated as much as desired this result may be accomplished by temporarily raising the forward corners of the movable bed section until the downwardly extending flange upon the front 10 side 58 clears the pins 52; then by moving the movable section rearwardly or the fixed section forwardly the two sections will be entirely separated.

What I claim as new and desire to secure 15 by Letters Patent is:

1. In a couch bed the combination of a relatively fixed bed section adapted to form the seat of a couch and having at its rear side near its corners two oppositely positioned rearwardly-extending brackets having a pin projecting from each one of the two brackets towards the other bracket and forming with the brackets and the adjacent rear portion of the fixed bed section two sockets, open at their top and open at their 20 ends that face each other and a movable bed section having a rigid rectangular frame including end rails and front and rear side rails and a bed surface carried by said frame and adapted when in upright position to form the back of the couch, the opposite front corners of the frame of the movable section being shaped to removably fit down into said two open-topped sockets with the front of said movable section positioned immediately to the rear of the fixed bed section, and to hold the movable section in upright couch-back position, each of said end rails being cut away at the forward end along the edge that is at the rear when the movable section is raised, the upper end of said cut forming a downwardly-facing shoulder when the section is raised which shoulder engages the pin on the bracket to stop downward movement of the movable section when it has come to desired 25 upright position.

2. In a couch bed the combination of a relatively fixed bed section adapted to form the seat of a couch and having at its rear side near its corners two oppositely positioned rearwardly-extending brackets having a pin projecting from each one of the two brackets towards the other bracket and forming with the brackets and the adjacent rear portion of the fixed bed section two sockets, open at their top and open at their 30 ends that face each other and a movable bed section having a rigid rectangular frame including end rails and front and rear side rails and a bed surface carried by said frame and adapted when in upright position to form the back of the couch, the opposite front corners of the frame of the movable section being shaped to removably fit down into said two open-topped sockets with the front of said movable section positioned immediately to the rear of the fixed bed section, and to hold the movable section in upright couch-back position, each of said end rails being cut away at the forward end along the edge that is at the rear when the movable section is raised, the upper end of said cut forming a downwardly-facing shoulder when the section is raised 35 which shoulder engages the pin on the bracket to stop downward movement of the movable section when it has come to desired upright position, said pins engaging with a loose pivotal action a portion of the front rail of the movable 40

section when it is raised and swung to bed-forming position.

3. In a couch bed the combination of a relatively fixed bed section adapted to form the seat of a couch and having at its rear side near its corners two oppositely positioned rearwardly extending brackets, each having a lug extending from a part of the bracket and forming with the bracket and the adjacent rear portion of the fixed bed section a socket, said two sockets being open at their top and open at their ends that face each other, and a movable bed section having a rigid rectangular frame including a front rail having near each end a projection extending downwardly from the front of the rail when the movable bed section is in horizontal position and a bed surface carried by said frame and adapted when in upright position to form the back of the couch, the opposite front corners of the frame of the movable section being shaped to removably fit down into said two open-topped sockets with the front of said movable section positioned immediately to the rear of the fixed bed section, and to hold the movable section in upright couch-back position, said movable section having foldable legs and being movable from couch-back position to bed-forming position by temporarily raising the movable section until the said projections on the front rail will engage and can loosely pivot about the lugs on the said brackets, which pivoting connection holds the two sections in double bed position, complete separation of said two sections being then allowable by temporarily raising the front of the movable section to disengage from said lugs on the brackets the open-bottomed hooks formed by the said downwardly extending projections on said front rail.

4. In a couch bed the combination of a relatively fixed bed section adapted to form the seat of a couch and having at its rear side near its corners two oppositely positioned rearwardly extending brackets, each having a lug extending from a part of the bracket and forming with the bracket and the adjacent rear portion of the fixed bed section a socket, said two sockets being open at their top and open at their ends that face each other, and a movable bed section having a rigid rectangular frame including a front rail having near each end an angle iron formation having one web thereof extend downwardly from the front of the other web when the movable bed section is in horizontal position and a bed surface carried by said frame and adapted when in upright position to form the back of the couch, the opposite front corners of the frame of the movable section being shaped to removably fit down into said two open-topped sockets with the front of said movable section positioned immediately to the rear of the fixed bed section, and to hold the movable section in upright couch-back position, said movable section having foldable legs and being movable from couch-back position to bed-forming position by temporarily raising the movable section until said angle iron formations on said front rail will engage and can loosely pivot about the lugs on said brackets, which pivoting connection holds the two sections in double bed position.

5. In a couch bed the combination of a relatively fixed bed section adapted to form the seat of a couch and having at its rear side near its corners two oppositely positioned rearwardly extending brackets, each having a lug extending from a part of the bracket and forming with the bracket and the adjacent rear portion of the fixed bed section a socket, said two sockets being open at their top and open at their ends that face each other, and a movable bed section having a rigid rectangular frame including a front rail having near each end a projection extending down-

wardly from the front of the rail when the movable bed section is in horizontal position and a bed surface carried by said frame and adapted when in upright position to form the back of the couch, the opposite front corners of the frame of the movable section being shaped to removably fit down into said two open-topped sockets with the front of said movable section positioned immediately to the rear of the fixed bed section, and to hold the movable section in upright couch-back position, said movable section having foldable legs and being movable from couch-back position to bed-forming position by temporarily raising the movable section until the said projections on the front rail will engage and can loosely pivot about the lugs on the said brackets, which pivoting connection holds the two sections in double bed position, complete separation of said two sections being then allowable by temporarily raising the front of the movable section to disengage from said lugs on the brackets the open-bottomed hooks formed by the said downwardly extending projections on said front rail.

6. In a couch bed the combination of a relatively fixed bed section adapted to form the seat of a couch and having at its rear side near its corners two oppositely positioned rearwardly extending brackets, each having a lug extending from a part of the bracket and forming with the bracket and the adjacent rear portion of the fixed bed section a socket, said two sockets being open at their top and open at their ends that face each other, and a movable bed section having a rigid rectangular frame including two end rails and front and rear side rails, said front rail having near each end a projection extending downwardly from the front of the rail when the movable bed section is in horizontal position and a bed surface carried by said frame and adapted when in upright position to form the back of the couch, the opposite front corners of the frame of the movable section being shaped to removably fit down into said two open-topped sockets with the front of said movable section positioned immediately to the rear of the fixed bed section, and to hold the movable section in upright couch-back position, said movable section having foldable legs and being movable from couch-back position to bed-forming position by temporarily raising the movable section until the said projections on the front rail will engage and can loosely pivot about the lugs on the said brackets, which pivoting connection holds the two sections in double bed position, each of said end rails of the movable bed section being cut away at the forward end along the edge that is at the rear when the movable section is raised, the upper ends of said cuts forming downwardly-facing shoulders when the section is raised which shoulders engage said lugs on said brackets and stop downward movement of the movable section when it has come to desired upright position.

7. In a couch bed the combination of a relatively fixed bed section adapted to form the seat of a couch and having at its rear side near its corners two oppositely positioned rearwardly extending brackets, each having a lug extending from a part of the bracket and forming with the bracket and the adjacent rear portion of the fixed bed section a socket, said two sockets being open at their top and open at their ends that face each other, and a movable bed section having a rigid rectangular frame including two end rails and front and rear side rails, said front

5 rail having near each end a projection extending downwardly from the front of the rail when the movable bed section is in horizontal position and a bed surface carried by said frame and adapted when in upright position to form the back of the couch, the opposite front corners of the frame of the movable section being shaped to removably fit down into said two open-topped sockets with the front of said movable section positioned immediately to the rear of the fixed bed section, and to hold the movable section in upright couch-back position, said movable section having foldable legs and being movable from couch-back position to bed-forming position by temporarily raising the movable section until the said projections on the front rail will engage and can loosely pivot about the lugs

10 on the said brackets, which pivoting connection holds the two sections in double bed position, complete separation of said two sections being then allowable by temporarily raising the front of the movable section to disengage from said lugs on the brackets the open-bottomed hooks formed by the said downwardly extending projections on said front rail, each of said end rails of the movable bed section being cut away at the forward end along the edge that is at 10 the rear when the movable section is raised, the upper ends of said cuts forming downwardly-facing shoulders when the section is raised which shoulders engage said lugs on said brackets and stop downward movement of the movable section when it has come to desired upright position. 15
